UNITED STATES PATENT OFFICE.

WALTER J. GADSBY, OF BOSTON, MASSACHUSETTS, ASSIGNOR TO THE ROXBURY CARPET COMPANY, OF SAME PLACE.

DESIGN FOR A CARPET.

SPECIFICATION forming part of Design No. 12,715, dated January 31, 1882.

Application filed December 29, 1881. Term of patent 3½ years.

To all whom it may concern:

Be it known that I, WALTER J. GADSBY, of Boston, in the county of Suffolk and State of Massachusetts, have invented a new and original Design for Carpets, of which the following is a specification.

The nature of my design is fully shown in the accompanying photographic illustration.

The design is composed of an aggregation of figures of various shapes, A B C D E, and floral and foliage ornamentation on a ground closely covered by net-work and other ornamentation in small lines and figures, as shown.

I claim—

The design for carpets, substantially as 15 shown and described.

In testimony whereof I have signed my name to this specification, in the presence of two subscribing witnesses, this 23d day of December, A. D. 1881.

WALTER J. GADSBY.
